UNITED STATES PATENT OFFICE.

WASHINGTON WHITNEY, OF SPRINGFIELD, MASSACHUSETTS, ASSIGNOR OF
ONE-HALF TO JENNIE E. DICKINSON, OF SAME PLACE.

DESIGN FOR A ROSETTE AND SLIDE FOR DOOR SPINDLE LOCK.

SPECIFICATION forming part of Design No. 12,581, dated November 22, 1881.

Application filed July 18, 1881. Term of patent 7 years.

To all whom it may concern:

Be it known that I, WASHINGTON WHITNEY, a citizen of the United States, residing at Springfield, in the county of Hampden and State of Massachusetts, have invented and produced a new and original Design for a Rosette and Slide for Door Spindle Locks, of which the following is a specification, reference being had to the accompanying drawings, forming part thereof.

Figure 1 is a sectional view of my newly-designed rosette, and Fig. 2 is a plan view of the rosette and slide.

The leading features of my design consist in making the border thereof of octagonal form, and the raised rim *a* around its center of corresponding shape, and in forming upon its face, the central portion of which sets out from the border part in curved form, ornamental figures, as hereinafter described.

The flat or border part of the rosette is divided into sections *c c*, *o o*, *e e*, and *i i*. Upon the ground or face of said sections I form a series of raised ornamental figures viz: In the sections *c*, I form a species of acute leaves having two lateral branches, and a central triangular figure between them. The sections *e* I ornament with one branch of said acute leaves. The sections *o* I ornament with a raised perforated ring and two diamond spots, one each side of said ring. The sections *i i* have each a raised triangularly-shaped figure thereon. The surface of the curved central portion of the rosette opposite the said sections *c c* of the border thereof is ornamented with like raised

figures to those upon said border-sections, but in an inverted position thereon, and the same figures are arranged opposite the sections *o o* of said border. The remainder of the surface of said curved central portion of the rosette is ornamented by grooves and lines, forming a groundwork between said first-named figures in the shape of a six-pointed star.

The exposed surface of the ends of the slide *b* may be ornamented with any desired figure 45 or figures appropriate to the above-described design upon the surface of the rosette.

I claim—

The design for a door spindle lock rosette, herein shown and described, the same consisting of a flat border portion of octagonal form, of a raised rim of like form, surrounding the center hole in the rosette, and an intermediate central portion, rising in curved lines above said border portion, said last-named border 55 having its face divided into sections *c c*, *o o*, *e e*, and *i i*, having thereon raised ornamental figures representing one and two branched acute leaves, together with triangular figures, raised perforate rings, and diamond-shaped 60 spots, and said intermediate central portion having likewise said acute leaf and triangular figures thereon, between which lies, in six-pointed-star form, a groundwork of raised lines and grooves.

WASHINGTON WHITNEY.
